COMBINED FUEL MIXER AND DEGASSER
FOR VEHICULAR INTERNAL COMBUSTION
ENGINES

Llewellyn T. Barnes, Hempstead, N. Y.

Application August 4, 1936, Serial No. 94,140

8 Claims. (Cl. 48—180)

My invention relates to improvements in combustible fluid charge-forming devices for multi-cylinder internal combustion engines, and is an improvement over the type shown in my application for a Carburetion device, Serial Number 12,920, filed March 25, 1935, and contemplates a combined homogenizing and degassing device adapted to improve the combustible mixture substantially throughout the entire operating range of the engine, particularly during idling thereof, and adapted to reduce the obnoxiousity of the exhaust gases of engines operating under varying power loads, particularly during or after "over-running" conditions as when the speed of the vehicle driven by the engine becomes greater than the idling speed of the engine and the engine is thus driven by the vehicle.

One of the main objects of the invention is to provide a simple, substantially unitary device having several desirable effects upon the stream of the combustible charge during certain conditions of operation and other desirable effects during other operating conditions, these desirable effects being produced by the novel arrangement of cooperating fuel and air passages in the single unitary device, easily installable in existing engines, and easily incorporated and made adaptable to engines having special fuel charging characteristics.

Another object of the invention is to improve the charge distribution among the several cylinders of an engine, whereby charge pulsations and flow-back of the charge in the manifold is reduced and whereby each of the cylinders receives a substantially equal charge quantitatively and qualitatively.

It is well known that vehicular internal combustion engines produce an obnoxious exhaust as the result of incomplete combustion of the fuel including lubricating oil sucked up into the combustion chamber during the high vacuum "over-running" condition mentioned, when the throttle valve of the carburetor is closed and the pistons are rapidly reciprocating, or during the idle running condition of the engine when the throttle is also fully closed.

It is further well known that during idling conditions the fluid fuel and air enter the intake manifold from an independent source other than the main mixture supply, said source usually provided by a by-pass or bleed opening in the interior surface of the carburetor conduit beyond the throttle valve and the main Venturi throat of the carburetor. This idling charge comprises an emulsion of air and liquid fuel and

in issuing from the idling jet opening is directed obliquely into the entrance conduit of the intake manifold in the form of a relatively wet stream and therefore enters the cylinders in a poorly atomized condition. The lack of proper intermixture of the air and liquid fuel in the throat of the main venturi of the carburetor and the passage of the idling charge into the smooth and non-turbulizing conduits of the intake manifold is not inducive to rapid, intimate and complete mixing, and proper atomization of the fluid fuel particles.

Accordingly, I propose the insertion of a venturi-like device actable upon the stream of the charge issuing from the main venturi of carburetor during the "cruising" range of the engine and actable upon the idling stream to assist in greater atomization thereof, said device being provided with means for creating greater intermixture and homogeneity of the liquid fuel particles and the air comprising the mixture during all operating conditions, said means permitting the entrance of an auxiliary supply of air to the mixture issuing from the carburetor beyond the main venturi and throttle. This auxiliary air not only serves to reduce the high vacuum in the cylinders when the throttle is closed during "over-running" conditions, but is also adapted and arranged so as to mix with the emulsified idling charge in the throat of this venturi-like device during normal idle-running conditions of the engine when high vacuum conditions are also present in the manifold system.

Other objects and advantages of the device are contemplated which will become apparent in the following description read in connection with the drawing forming part of my disclosure, in which:—

Fig. 1 is a perspective view of my device.

Fig. 2 is a side elevation of an engine partly in section, showing my device with a carburetor and an intake manifold in position employed in a vehicular internal combustion engine.

Fig. 3 is an enlarged sectional view of a portion of Fig. 2.

Fig. 4 is a section taken on the line 4—4 of Fig. 3.

Figs. 5 and 6 are diagrammatic views of an engine similar to that shown in Fig. 2 and illustrate modified applications of my device.

Fig. 7 is a fragmentary sectional view of a portion of further modification of my device.

Referring to Fig. 1, a multi-cylinder engine is provided with an intake manifold generally indicated at 11 having a main inlet or trunk port

tion 12 and branches 13 to the separate cylinders of the engines.

Between the exit portion of the carbureter 20 and the inlet portion 12 of the intake manifold 5 providing a conduit for the passage of fluid fuel, I provide a unitary homogenizing and degassing device 14 comprising a tubular venturi-like body 15 providing internally thereof an arcuate throat 16 and a conical entrance mouth portion 17. This 10 mouth portion 17 is of such size as to embrace a major portion of the stream of fuel and air mixture issuing from the main venturi of the carbureter into the exit portion 19 of the carbureter. Preferably integrally formed with the 15 body 15 on the downstream side of the throat there is provided a skirt portion 21, extending into the intake manifold trunk portion. The embracing or cross-sectional area of this skirt portion being less than the area of the base of 20 the conical mouth portion 17 of the venturi-like device, forms an extension of the throat. The area of the passage provided by this skirt portion is relatively much less than the cross sectional area of the conducting passage provided 25 by the trunk portion 12 of the intake manifold, thus providing an expansion space immediately beyond the skirt portion.

In order to prevent the too sudden expansion of the stream beyond the free end of the skirt, I 30 provide a plurality of slots 18 in the skirt. The slots are V-shaped which allows a gradual expansion of the stream in a divergent path to simulate the effect of a fully confined venturi. The exit portion of the stream is thus confined substantially as indicated by the dot and dash lines 35 in Figure 2. This construction also provides a flow-back check for dampening the vapor surges in the manifold, which will be more fully described later.

40 Preferably, but not essentially, integrally formed with the body 15 and exteriorly thereof, is a transversely directed annular mounting flange 22. This flange 22 is disposed substantially in the plane of the arcuate portion of the 45 throat 16 but may be arranged higher or lower on the body 15 of the device so as to position the venturi more or less into the trunk of the manifold. This flange is provided with a plurality of radially disposed holes 23, the purpose of which 50 will be later described.

The flange 22 may be made flexible or yielding to serve as a seal against air leak. By providing an annular channel 24 in the external portion of the flange 22, two relatively thin and flexible 55 flanges 25 and 26 are provided which are adapted to be yieldingly clamped between the flanges 27 and 28 of the intake manifold and the carburetor, respectively. Separate gaskets or other means for sealing the device against leakage may be 60 provided if desired.

A space or gap 29 is thus provided between the carburetor and manifold flanges, which space allows communication of the throat of the venturi with the outside atmosphere via the holes 23.

65 In the exit conduit 19 of the carburetor a throttle valve 31 is usually provided, which is in the form of a butterfly valve, and is disposed after the main venturi 32 of the carburetor relative to the direction of flow.

70 The upstream extremity of the mouth portion 17 of the venturi is spaced as at 33 from the internal surface 34 of the carburetor exit conduit 19. The exterior surface of the conical mouth portion is inwardly directed to form an annular 75 pocket 35 which communicates with the throat

through angularly and upwardly directed holes 36 terminating in the throat and passing thru the juncture of the conical entrance portion 17 and the flange 22.

Under normal operating or "cruising" conditions (throttle partly open) a substantial reduction of pressure is created at the throat 16 of the device, thus drawing any liquid or "heavy ends", comprising relatively large liquid particles which happen to be trapped in the pocket, into the throat via the holes 36, whereupon the liquid fuel or liquid particles reaching the pocket 35 are subject to intimate dispersion by intimate contact with the incoming auxiliary air entering the throat through holes 23.

15 During "cruising" conditions when the engine is under load and propelling a vehicle, the major portion of the charge issuing from the carbureter passes through the conical entrance portion of the device, and the fuel trapped by the pocket 20 is mixed with a relatively small or insignificant quantity of auxiliary air due to the preponderance of primary air passing thru the main venturi of the carburetor. The air to fuel ratio is relatively constant under these relatively large 25 volumetric requirements since the small amount of auxiliary air does not disturb this ratio over a wide "cruising" range. Although the auxiliary air holes provide a constant intake area the volume of auxiliary air passing therethru varies in 30 accordance with the power requirements.

35 In some cases the normal setting of a carburetor is unchanged in that the additional supply of auxiliary air is not critical over the major portion of the higher power output range, but this additional supply of air is very vital in the lower operating range, particularly during idling conditions (throttle closed) or in the power output range slightly higher or above the idling range. In the higher power output range the 40 auxiliary air, however, provides jets of pure air which aids in assimilating and vaporizing the liquid creepage along the wall 34 and heavy ends of the liquid particles, which are forced outwardly in the conduit 19 and ultimately enter the annular pocket 35. The number of holes 22 and/or 45 36 may be varied so as to provide the proper amount of auxiliary air or sufficient pocket passages, but I have found that an equal number of auxiliary air and pocket holes equally and alternately spaced around the throat amply accommodates a wide range of variation in volumetric 50 requirements.

55 During idling conditions, however, when the throttle is closed or substantially closed and the emulsified charge is fed through a small opening 55 (or openings) 36 in the side wall 34 of the exit conduit 19 of the carburetor, most of the idling mixture enters the pocket 35, due to the poor directional dispersion and the disorderly entrance of this idling charge. The idling charge with the aid of my device 14 is, however, mixed with the auxiliary air at the throat of the venturi 15, thus providing an orderly and intimate and greatly improved mixture of air with the poorly 60 vaporized idling mixture, thus creating an improved atomization of the charge beyond the throat of the Venturi device 14 allowing a greater air to fuel ratio to form the combustible mixture in the lower speeds. It may be found necessary to 65 decrease the amount of idling air through the idling jet 38 to compensate for the additional auxiliary air taken in through the holes 23. This adjustment is, however, not critical, in that the greater intimacy of the air and the fuel particles 70 75

permits the introduction and assimilation of additional air for a given amount of fuel issuing from the idling jet, thus increasing the efficiency of the engine in the idling range and resulting in a higher idling speed for the same amount of fuel by comparison with an engine operating under the same conditions without the novel device. Economical idling is thus effected and maintained in that the amount of auxiliary air drawn into the throat varies with the condition of vacuum which in turn varies with the speed of the engine.

During "over-running" operating conditions when the pistons are reciprocating rapidly and the throttle is closed, creating a corresponding high vacuum in the cylinders and in the intake manifold, the auxiliary air is drawn through the openings 23 at relatively high velocity and assists in breaking this high vacuum in the cylinders, thus preventing oil from entering the combustion chamber, later to be burned and passed out through the exhaust. This provides "degassing" of the exhaust. By "degassing" is meant, the elimination of obnoxious odors of incomplete combustion of certain components of the lubricating fluids other than the fluids intended to provide the combustion.

It will therefore be seen that the auxiliary air holes in the throat of the venturi not only provide air to mix with the charge issuing from the carburetor to aid in producing a higher degree of atomization of the liquid fuel particles during the entire "cruising" range, but also aids in providing auxiliary air to form a more effective and properly atomized charge during idling condition, and further, this auxiliary air supply functions to break the high vacuum in the low speed or idling range.

By such construction of the venturi-like device just described, it will be noted that free and easy flow is afforded the stream in one direction, (indicated by arrow in Figure 2) and that a relatively interrupted and tortuous flow is effected on the stream in the opposite direction.

Due to sudden interruption of the stream flowing at high velocity, as occurs upon sudden closing of the intake valves, the rebound of the stream tending to flow back thru the carburetor is retarded or damped by my device. This above mentioned resistance to free flow in the opposite direction is caused by the eddy currents and frictional resistance set up by the lack of stream lines in the structure of the skirt portion.

By providing a venturi-like device similar to the one shown in detail in Figure 2, at the extremity of each of the branches 13, or in the cylinder port, substantially ahead of the inlet valves of the engine, additional flow-back check is afforded which supplements the action of the Venturi device in the inlet trunk conduit 12. This is illustrated in Figure 5, the individual Venturi devices being shown in dotted lines and indicated by the reference character 41. The devices 41 may have holes such as 23 and 36 for the purpose set forth or the holes may be eliminated. In some cases it has been found desirable to omit the holes in certain of the devices, some of the remaining devices in the engine being provided with pocket by-pass holes only, and other of the remaining devices being provided only with auxiliary air holes.

It will be understood that I am not limited to the introduction of only auxiliary air and that any other fluids may be caused to flow thru the auxiliary air holes 23. The holes 36 may be of con-

verging (in the direction of flow) conical formation, which creates a Venturi effect upon the liquid or emulsion passing therethru. This is shown in Figure 7.

As seen in Figure 6, in some cases the main venturi-like device need not be employed in the trunk of the intake manifold, and a venturi-like device may be employed only at the exit of some of the branches of the manifold.

It is to be understood that various arrangements and dispositions of the devices may be had depending upon particular characteristics of the engine.

Although I have shown and described the preferred construction of my device, it will be noted that minor changes may be made without departing from the principles of its operation.

What I claim as new and desire to secure by Letters Patent, is:

1. In combination with an engine having an intake manifold, a carburetor having an exit passage for fluid issuing therefrom, a venturi-like device between the carburetor and the intake manifold and in the path of fluid flowing from said carburetor to said manifold, said device comprising an internally converging conical portion forming a mouth and a reduced throat, said mouth adapted to embrace substantially the entire area of said exit passage, thereby affording unrestrictive access to substantially all of the fluid issuing from the carburetor and into said device, a flange for supporting said device and for maintaining it in the path of flow of fluid issuing from said carburetor, and a substantially cylindrical skirt portion merging with and of substantially the same passage area as the area of said throat portion and extending from said flange in the direction of flow, said skirt portion being materially spaced from the walls of said manifold, thereby forming an annular pocket, 40 said skirt being provided with means affording lateral passage of the fluid through said skirt whereby expansion and uninterrupted flow of the fluid is afforded in the direction toward the engine, said annular pocket causing fluid flowing 45 in the opposite direction to take a circuitous path through said lateral passage means in said skirt whereby back-flow of the fluid is retarded during back-surge of the fluid.

2. In combination with a fluid fuel induction internal combustion engine, an apparatus of the character described including a conduit, a one-piece venturi-like body in said conduit, means for maintaining said body immovably in said conduit and in sealed engagement with said conduit, said body having an internally converging conical mouth portion extending axially and spaced from said conduit, thereby forming an annular pocket at the juncture of said means and said body, said pocket adapted to receive fuel passing through said body and said conduit, means providing communication between said pocket and the interior of said venturi-like body whereby any fluid fuel coursing in said conduit and entering said pocket is afforded exit into the interior of said body, and means affording communication between the interior of said body and the exterior of said conduit whereby other fluid from a source external of said conduit is afforded access to the interior of said body.

3. In combination with a fluid fuel induction internal combustion engine, an apparatus of the character described including a conduit, a one-piece venturi-like body in said conduit, means for maintaining said body immovably in said

- conduit and in sealed engagement with said conduit, said body having an internally converging conical mouth portion extending axially and spaced from said conduit, thereby forming an annular pocket at the juncture of said means and said body, said pocket adapted to receive fuel passing through said body and said conduit, means providing communication between said pocket and the interior of said venturi-like body whereby any fluid-fuel coursing in said conduit and entering said pocket is afforded exit into the interior of said body, and means affording communication between the interior of said body and the exterior of said conduit whereby other fluid from a source external of said conduit is afforded access to the interior of said body, said first and second means of communication terminating internally of said body substantially in the same transverse zone of said body.
4. In combination with a carburetor and an intake manifold providing a common conduit, a one-piece venturi-like body in said conduit and between said carburetor and said intake manifold, flange means for maintaining said body immovably in said conduit in sealed engagement with said conduit, a converging conical mouth portion on the upstream side of said body and extending from said means toward said carburetor and spaced from said conduit forming an annular pocket bounded by said mouth portion, said means, and said conduit, means affording communication of said pocket and the interior of said body, whereby any fluid in said pocket is afforded access to the interior of said body, said body having a substantially cylindrical skirt portion extending in the direction of flow and having a smaller external diameter than the initial entrance diameter of said conical mouth portion, and slots in said skirt portion affording gradual expansion of the fluid during its passage in said skirt toward the manifold, said skirt being spaced from said conduit, said flange means forming a bar between said skirt and said conduit whereby fluid flowing in the opposite direction is caused to enter the interior of said body in a tortuous path and through said slots.
5. In combination with a conduit, a device of the character described comprising a venturi-like body having a converging conical mouth por-

tion, a throat portion at the end of said mouth portion and providing a minimum passage area through said venturi-like body, a skirt portion coextensive with said throat portion, a flange external of said body and of greater outer dimension than said mouth portion and extending transversely to the axis of said body, said flange adapted to be secured to said conduit, said mouth being spaced from said conduit to form an annular pocket in communication with the upstream side of said conduit, said pocket being disposed at the juncture of said body and said flange, means providing communication between said pocket and said throat, and means providing communication between the interior of said venturi-like body substantially at said throat and the exterior of said conduit.

6. A combined fluid fuel mixing and degassing device adapted for insertion at the juncture of a separable induction conduit directing the flow of atomized fuel to an internal combustion engine, said device comprising a one-piece cylindrical venturi-like body providing a continuous passage internally thereof for said atomized fuel; said passage comprising a mouth adapted to form a converging entrance for said fuel, a throat formed by a restricted portion of said passage merging with said mouth, and a substantially cylindrical exit portion continuing beyond said throat in the direction of flow, a flange on the exterior of said body adapted for sealed engagement with spaced abuttable surfaces of said portions of said conduit, whereby said body is maintained within the conduit, and holes in said flange, whereby said throat is communicative with the atmosphere outside the conduit and whereby only auxiliary air is admittable into said passage to mix initially at the throat with said atomized fuel.

7. The combination with a carburetor and an intake manifold of a device as claimed in claim 6 disposed substantially between the adjacent flanges of a carburetor and an intake manifold.

8. The combination with an engine and intake manifold of a device as claimed in claim 6 disposed substantially between the engine and the intake manifold.

LLEWELLYN T. BARNES.
